(57) **CLAIM**

The ornamental design for a display screen with graphical user interface for trading system data, as shown and described.

DESCRIPTION

FIG. 1 is a front view of a display screen with graphical user interface for trading system data showing our new design; and,

FIG. 2 is a front view of a display screen with graphical user interface for trading system data showing an alternative embodiment of our new design.

The broken line showing of the outer rectangular display screen and the remainder of the graphical user interface forms no part of the claimed design.

1 Claim, 2 Drawing Sheets

FIG. 1

FIG. 2
